G. W. HULSHIZER

AIR FEED CONTROL FOR ROCK DRILLS

Filed Feb. 18, 1924

UNITED STATES PATENT OFFICE.

GEORGE W. HULSHIZER, OF STEWARTSVILLE, NEW JERSEY, ASSIGNOR TO INGER-SOELL-RAND COMPANY, OF JERSEY CITY, NEW JERSEY, A CORPORATION OF NEW JERSEY.

AIR FEED CONTROL FOR ROCK DRILLS.

Application filed February 18, 1924. Serial No. 693,479.

This invention relates to fluid pressure operated rock drills of the hammer type, but more particularly to an air feed control for the feeding element which advances the machine. The invention is especially applicable to a stope drill, although it may be advantageously used in connection with drifters and other types of rock drills for drilling horizontal and down holes.

10 In operating a stope drill for instance, which may be taken as an illustrative example, if a soft spot is encountered, the power of the air feed should ordinarily be reduced, but full rotation and hammer power

15 retained to enable the machine to operate in the most efficient manner.

The object of the present invention is to enable the air feeding element of a rock drill to be readily controlled in an improved and simplified manner by the operator without removing his hand from the rotation handle.

Another object of the invention is to enable the feeding element of a rock drill to be controlled by a valve which is adapted to control the supply of pressure fluid to the feeding element and is also adapted to bleed pressure fluid from the feeding element at the will of the operator.

30 A further object of the invention is to enable a valve which is adapted to control the feeding element of a rock drill to be locked in different positions.

Further objects of the invention will hereinafter appear and the invention is shown in one of its preferred forms in the accompanying drawings in which,

Figure 1 is a side elevation partly in vertical section of a stope drill embodying the present invention;

Figure 2 is an enlarged vertical section of the rotation handle shown in Figure 1; and

Figure 3 is a transverse section taken on the line 3-3 of Figure 2, looking in the direction of the arrows showing the teeth on the top of the actuating sleeve.

Referring to the drawings, A designates the cylinder of a fluid actuated stope drill to which is connected a front head B which is adapted to receive the drill steel C. The cylinder A and front head B are preferably connected together by the usual spring pressed side bolts D. The drill steel C is adapted to receive the impact blows of the

hammer piston, which forms a percussive element of the machine, located in the cylinder A, and the drill steel may be rotated by any suitable means, but in this instance is rotated by an independent rotation motor 60 located in the casing E.

The feeding element of the machine in this instance comprises a cylinder F in which is located a piston G to which is connected a piston rod H carrying the usual rock engaging pointer J. The head block K is in this instance located between the feed cylinder F and the motor casing E, and pressure fluid is supplied to the machine through a suitable connection L. A suitable valve 70 having an actuating handle O is adapted to control the admission of pressure fluid to the percussive element and the feeding element in any suitable manner. A rotation handle P, preferably having an extension Q, 75 is in this instance connected to the head block K by a nut R screwed onto the threaded end portion S of the handle P.

In accordance with the present invention, the rotation handle P is formed with a hollow bore T and pressure fluid is adapted to pass to the feed cylinder F from the throttle valve, through a port U in the head block K, and through a port V in the rotation handle P and into the reduced bore W in the rotation handle, and then through a port X in the rotation handle which is preferably in staggered relation to the port V, and from the port X through the passage Y into the feed cylinder F.

In order to control the passage of pressure fluid to the feed cylinder F, a valve Z is slidably mounted in the rotation handle P, and is preferably formed with a head a which is adapted to slide in the bore W, a central head b which is adapted to slide in the larger bore T, and an outer head c also adapted to slide in the bore T. The heads a and b are connected together by the stem d, and the heads b and c are connected together by the stem e. The stem d is preferably formed with a hollow bore f which communicates at one end with an annular groove g in the head a by means of a port h, and the opposite end of the bore f communicates with the hollow bore T of the rotation handle P by means of a port i in the head b. The head c is in this instance formed with a port k, and one end of the bore T is closed by a screw threaded plug 110

o, which is provided with an atmospheric vent *p* which port connects a portion of the hollow bore *T* with the atmosphere.

- In order to actuate the valve *Z* in one direction, a stem *q* is preferably located in the bore *r* of the rotation handle extension *Q* and is formed at one end with a cam *s* against which the end *t* of the valve head *c* is adapted to bear. A coil spring *u* in this instance bears against the head *b* of the valve *Z* at one end and a shoulder *b'* in the rotation handle of the opposite end and forces the end *t* of the valve *c* against the cam *s*. In order to rotate the stem *q*, a knurled sleeve *v* preferably having one end *w* closed is mounted on the rotation handle extension *Q* and the stem *q* is in this instance connected to rotate with the sleeve *v* by a suitable pin *x*. The stem *q* is preferably formed with a reduced end portion *y* and a screw threaded bushing *z* prevents the stem *q* from sliding from the extension *Q* when the sleeve *v* is removed from the extension *Q*.
- 25 A collar *2* is in this instance mounted on the rotation handle extension *Q* to slide on the perimetric surface thereof and is preferably formed with a keyway *3* into which extends a key *4* carried by the extension *Q* so that the collar *2* may slide longitudinally on the extension *Q* but is prevented from turning. The sleeve *v* is in this instance formed with ratchet teeth *5* and the collar *2* is also formed with ratchet teeth *6* which bear against the ratchet teeth *5*. A coil spring *7* bears against the rotation handle *P* at one end and against the collar *2* at the opposite end and serves to hold the ratchet teeth *5* and *6* together.
- 40 In the operation of the device by turning or rotating the knurled sleeve *v*, the stem *q* will be turned or rotated so that the cam *s* will bear against the end *t* of the valve head *c* and move the valve *Z* longitudinally in the rotation handle *P*. Whenever a soft spot is encountered by the drill steel, the power of the air feed should ordinarily be reduced, but full rotation and hammer power retained, and in such a case the sleeve *v* will be rotated to move the valve *Z* until the head *a* reduces the flow of air into the air feed cylinder *F* by reducing or, if desired, entirely closing the port *X* in the rotation handle *P*. In this manner the power of the air feed may be readily reduced by reducing the flow of pressure fluid to the air feed cylinder, and, if it is desired to shut off the feed entirely, this also may be accomplished by moving the valve *Z* to entirely close the port *X*.

Whenever it is desired to further reduce the power of the air feed some of the pressure fluid from the air feed cylinder *F* may be bled to atmosphere by further rotating the knurled sleeve *v* so that the annular

groove *g* in the head *a* registers with the port *X* whereby pressure fluid will pass from the feed cylinder *F* through the port *X*, annular groove *g*, port *h*, the hollow bore *f* of the valve *Z*, port *j* and through the bore *T* of the rotation handle and ports *k* and *p* to atmosphere. The operator is thus enabled to readily control the air feed in a simple and convenient manner without removing his hand from the rotation handle.

Whenever the sleeve *v* is turned or rotated to a desired position the ratchet teeth *5* and *6* on the sleeve *v* and the collar *2* respectively will serve to lock the valve *Z* in whatever position the operator desires it to remain, and when it is desired that the feeding element operate normally, the sleeve *v* may be rotated in the opposite direction and the coil spring *u* will return the valve *Z* to its normal position. It will be observed that the sleeve *v* may be rotated in either direction, either a partial or a complete revolution about the extension *Q*, to actuate the valve *Z* because the cam *s* will operate against the end *t* of the valve head *c* in either direction the stem *q* is rotated.

I claim:

1. In a rock drill the combination with an element to be controlled and a source of pressure fluid supply, of a handle, ports through the handle for admitting pressure fluid from the source of supply to the element to be controlled, a longitudinally movable valve in the handle for controlling the flow of pressure fluid into the element to be controlled, said valve having a transverse passage adapted to register with one of the ports for releasing pressure fluid from the element to be controlled, a passage longitudinally through the valve communicating with the transverse passage and with the atmosphere, a stem mounted rotatably in the handle, a cam on the stem for actuating the valve in one direction to place the element to be controlled in communication with the atmosphere, a spring for moving the valve in the other direction and for holding said valve in constant contact with the cam, a rotatable sleeve on said handle and secured to the stem for manipulating the cam, said sleeve being adapted to describe a complete revolution about the handle, a spring pressed collar slidable on the perimetric surface on the handle to cooperate with the sleeve for holding the cam in an adjusted position, and means for holding the collar against rotation with respect to the handle.

2. In a rock drill the combination with an element to be controlled and a source of pressure fluid supply, of a handle, ports through the handle for admitting pressure fluid from the source of supply to the element to be controlled, a valve longitudinal-

- ly movable in the handle for controlling the flow of pressure fluid through the ports, a transverse passage adapted to register with one of the ports, a passage longitudinally through the valve communicating with the transverse passage for conveying pressure fluid from the element to be controlled to the atmosphere, a stem rotatable in the handle, a cam on one end of the stem for actuating the valve in one direction, a spring encircling the valve for moving the valve in the opposite direction and for pressing one end of the valve constantly against the cam, a sleeve rotatable on the handle connected to rotate the stem, ratchet teeth on one end of the sleeve, a collar slidable on the handle and having ratchet teeth to cooperate with the ratchet teeth on the sleeve for holding the cam in an adjusted position, means for holding the collar against rotation with respect to the handle, and a spring around the handle for holding the ratchet teeth on the sleeve and on the handle in engagement with each other.
